ATTORNEY

UNITED STATES PATENT OFFICE

EUGENE F. CLARK, OF DAMARISCOTTA, MAINE, ASSIGNOR TO MARSHALL FIELD MILLS CORPORATION, OF PHILADELPHIA, PENNSYLVANIA, A CORPORATION OF PENNSYLVANIA

YARN-POSITIONING DEVICE FOR LOOMS FOR WEAVING TUFTED PILE FABRIC

Application filed February 5, 1929. Serial No. 337,627.

This invention relates to improvements in yarn positioning devices for looms for weaving tufted pile fabric of the general character of the loom illustrated and described in my previous Letters Patent No. 1,594,605, dated August 23, 1926.

The object of my present invention is to improve the yarn positioning devices of the aforesaid loom by the addition of yieldable or spring means constructed and arranged to act upon the yarn positioning blades to hold them normally in substantially parallel relationship and to return them to their normal position when they are moved therefrom against the action of the spring means and released and to permit them to have independent lateral movement against the spring means so that they may engage the yarn guiding tubes of a tube frame and accommodate themselves to any irregularities which may be present in the tubes and the spaces between them as the blades are moved into such spaces.

The invention consists of the elements and combinations of them hereinafter described.

In the accompanying drawings illustrating the invention,

Figure 1 is a top view of a yarn positioning device embodying my invention showing parts of the blade carrying bar broken away and illustrating the positions of the tubes of a tube frame in the position they occupy with relation to the yarn positioning blades before the blades are moved into the spaces between the tubes.

Figure 2 is a vertical section through the blade carrying bar, on line 2—2 of Fig. 1.

Figure 3 is a top view enlarged of a portion of the blade carrying bar showing a blade therein moved laterally in one direction from its normal position against the action of its spring means.

Figure 4 is a similar view showing a blade moved laterally in the opposite direction against the action of its spring means.

Figure 5 is an end view of one of the blades, enlarged.

Figure 6 is a side view of one of the blades. Referring to the drawings 3 designates a

bar and 4 a row of yarn positioning blades which project from the bar 3 in lateral spaced relation to each other.

The bar 3 carrying the blades 4 is adapted to be supported and actuated with relation to the tubes of the tube frames and the grippers for receiving the yarn from the tube frames for causing the blades 4 to position the yarn with respect to the grippers in a loom for weaving tufted pile fabric in the same manner that the bar "87" is supported and actuated with relation to the tubes "30" of the tube frames "20" and the yarn grippers "31" for causing the blades "113" carried by the bar "87" to position the yarn from the tubes "30" with respect to the grippers "31" of the loom illustrated and described in the aforesaid Letters Patent No. 1,594,605.

The yarn positioning blades 4 extend toward the position occupied by the tubes, indicated at 5 in Fig. 1, of a tube frame when the bar 3 is in a loom. The blades 4 are arranged with their sides in vertical position so that the spaces between them will be aligned with and opposite to the tubes 5 and the grippers (not shown) beneath the tubes 5 to receive yarn therefrom.

The blades 4 are shaped as clearly shown in the drawings, and they are set in transverse grooves 6 formed in the bar 3 and they are retained therein by a rod 7 which is located within a longitudinally extending groove 8 in the bar 3. The rod 7 extends through the groove 8 and through aligned notches 9 in the upper edge portions of the blades 4. The rod 7 is held in place within the groove 8 and notches 9 by a bar of angle iron 10 having one flange thereof extending over the top of the bar 3 and over the rod 7 and having the other flange thereof extending adjacent to one of the longitudinal vertical sides of the bar 3 and secured thereto by screws 11.

Arranged within the transverse grooves 6 of the bar 3, one adjacent to each blade 4, are a set of bow springs 12, each spring being formed of suitable spring sheet metal and shaped as shown in the drawings. The end portions of each spring 12 press against one side wall of the groove 6 in which it is located.

cated, and the central portion of each spring 12 presses against the adjacent blade 4 and presses it toward the opposite side wall of the groove 6 in which the spring is located. The springs 12 are held in place within the grooves 6 by the rod 7 which extends through notches 13 in the springs.

10 The central portions of the springs 12 exert pressure in the same direction and press the blades against the opposing side walls of the grooves 6 and maintain them yieldingly against such walls in the normal or inactive position of the bar 3 and blades 4, as shown in Fig. 1 of the drawings.

15 The grooves 6 are uniformly spaced along the bar 3 with the distance between the parallel side walls of each groove somewhat greater than the combined thicknesses of the blade 4 and spring 12 therein so that the springs 12 will hold the blades 4 normally in parallel, spaced relation to each other with equal spaces between them and yet permit each blade to be moved laterally independently of and relatively to the other blades either in 20 one direction from the normal position of the blade, as shown in Fig. 3, or in the reverse direction from the normal position of the blade, as shown in Fig. 4. Thus it will be understood that the free end portions of the 25 blades may be moved laterally in either direction independently of each other against the action of the springs when pressure is applied to the blades, and that after such pressure is removed the springs will return the 30 blades to the normal position thereof.

35 The tubes or yarn guides 5 of the tube frames are wedge shaped in cross section so that their diverging side walls will form spaces between tubes having wide entrance 40 openings facing the yarn positioning blades to ensure the entrance of the blades 4 into such spaces irrespective of any slight irregularities which may be present in the spaced relation of the tubes due to the accidental bending thereof when in service or due to 45 other causes; so that, while the walls of the slots 6 and the springs 12 will hold the blades 4 normally in parallel relation and in registry with the normal spaces between the tubes 50 5, the springs 12 will permit any of the blades 4 to be moved laterally by the tubes 5 should any of the blades encounter any of the tubes when the bar 3 is operated to move the blades into the spaces between the tubes. Should 55 any of the blades 4 be moved laterally by encountering any of the tubes 5 the springs 12 will return such blades to normal position relatively to the bar 3 when the bar is returned to the normal position shown in Fig. 1.

60 The portion of each blade 4 which projects from the bar 3 and which is adapted to enter a space between two adjacent yarn guiding tubes 5 has its opposite flat side surfaces converging upwardly from the bottom thereof to 65 a knife-like edge at the top thereof to con-

form to the angles of the opposing sides of the tubes 5 which are set at similar angles, to lessen the liability of the blades encountering the walls of the tubes as the blades are moved into the spaces between them.

70 I claim as my invention:

1. A yarn positioning device for looms for weaving tufted pile fabric, comprising a bar provided with a row of yarn positioning blades extending therefrom in spaced, substantially parallel relationship in the normal position of the blades, and spring means acting upon the blades, the blades being capable of independent lateral movement from the normal position thereof against the action 75 of said means.

2. A yarn positioning device for looms for weaving tufted pile fabric, comprising a bar provided with transverse parallel grooves, a row of yarn positioning blades within the grooves and extending from the bar, means to retain the blades within the grooves, and spring means acting upon the blades, the blades being capable of independent lateral movement against the action of said means. 80

3. A yarn positioning device for looms for weaving tufted pile fabric, comprising a bar provided with transverse parallel grooves, a row of yarn positioning blades within the grooves and extending from the bar, springs 95 within the grooves acting upon the blades, and a common means for retaining the blades and springs within the grooves, the blades being capable of independent lateral movement against the action of the springs. 90

4. A yarn positioning device for looms for weaving tufted pile fabric, comprising a bar provided with transverse parallel grooves, a row of yarn positioning blades within the grooves and extending from the bar, a spring 105 within each groove pressing the blade therein normally against one side wall of the groove, the blades being capable of independent lateral movement against the action of the springs. 110

5. A yarn positioning device for looms for weaving tufted pile fabric, comprising a bar provided with transverse parallel grooves, a row of yarn positioning blades within the grooves and extending from the bar, a bow 115 spring within each groove having its end portions pressing against one side wall of the groove and having its central portion pressing against the blade within the groove and pressing the blade against the opposite side wall of the groove, the blades being capable of independent lateral movement against the action of the springs. 120

6. A yarn positioning device for looms for weaving tufted pile fabric, comprising a bar provided with transverse parallel grooves and a longitudinal groove intersecting the transverse grooves, a row of yarn positioning blades within the transverse grooves and extending from the bar and having notches 125 130

therein alined with the longitudinal groove, a retaining rod within the transverse groove and said notches, means to hold the rod in place, and spring means acting upon the blades and retained within the transverse grooves by the rod, the blades being capable of independent lateral movement against the action of said means.

7. A yarn positioning device for looms for weaving tufted pile fabric, comprising a bar provided with transverse parallel grooves and a longitudinal groove intersecting the transverse grooves, a row of yarn positioning blades within the transverse grooves and extending from the bar and having notches therein alined with the longitudinal groove, a bow spring within each groove having its end portions pressing against one side wall of the groove and having its central portion pressing against the blade within the groove and pressing the blade against the opposite side wall of the groove, the blades being capable of independent lateral movement against the action of the springs, each spring having a notch therein alined with the notches in the blades, a retaining rod within said notches and the longitudinal groove, and means to hold the rod in place.

In testimony whereof I affix my signature.
